UNITED STATES PATENT OFFICE.

LEON M. LITTLE, OF DUBLIN, GEORGIA.

FIRE ESCAPE.

Application filed August 21, 1923. Serial No. 658,635.

To all whom it may concern:

Be it known that I, LEON M. LITTLE, a citizen of the United States, residing at Dublin, in the county of Laurens and State 5 of Georgia, have invented certain new and useful Improvements in Fire Escapes, of which the following is a specification.

This invention relates to fire escapes, and has special reference to a fire escape for 10 schools and other like buildings.

One important object of the invention is to improve the general construction of devices of this character.

A second important object of the invention 15 is to provide an improved fire escape of the sliding chute type.

A third important object of the invention is to provide an improved fire escape where- 20 in the chute will be made of flexible material and in which, under ordinary circumstances, the chute will be rolled up out of reach when not in use.

A fourth important object of the invention 25 is to provide an improved device of this character which will be readily accessible from one window of each floor of a building.

With the above and other objects in view, as will be hereinafter apparent, the invention consists in general of certain novel de- 30 tails of construction and combinations of parts hereinafter more fully described, illus- trated in the accompanying drawings and specifically claimed.

In the accompanying drawings like char- 35 acters of reference indicate like parts in the several views, and:

Fig. 1 is a side elevation partly in sec- 40 tion disclosing a portion of a building with the improved fire escape in position thereon.

Fig. 2 is an enlarged detail section on the line 2—2 of Fig. 1.

Fig. 3 is an enlarged longitudinal section 45 of a portion of the device.

Fig. 4 is a detail section on the line 4—4 of Fig. 3.

Fig. 5 is a detail section through the chute 50 folded up in its normal position when not in use.

Figure 6, is a detailed perspective show- 55 ing certain means for holding the side walls of the chute in direct position.

In the embodiment of the invention herein 60 illustrated, there is shown a building having a wall 10 provided with a series of window openings indicated at 11. Secured by brackets 12 to the wall is a pair of spaced

confronting angle irons 13 having horizontal leg portions extending toward each other and provided with upstanding spaced pins 14 arranged opposite each other on the two angle irons. About these angle irons are arranged a pair of T irons or rails 15 supported by suitable struts 16. On the rails 15 rests a roller or axle 17 which is provided at each end with a grooved rope 60 pulley 18. Mounted on the upper ends of the rails 15 is a winding drum 19 around which is wound the ropes 20, said ropes being led around the pulleys 18 and back to- 65 wards the winding drum where they are se- cured to suitable castings 21 mounted on the rails 15. This winding drum is also pro- 70 vided with a ratchet 22 engaged by a pawl 23 which is controlled by a cord or wire 24, which may either run down the outside of 75 the building or through the inside thereof adjacent the windows 11.

It is to be observed that the inclination of the structure just described is such that it is 80 convenient of access from at least one window on each floor, and that the lower ends of the rails 15 are inclined downwardly at the bottom, as shown at 25 in Fig. 1. Ad- 85 jacent these downwardly inclined portions, there is provided suitable latch means as 26 which may be swung over and hooked around the axle 17 when the latter rolls down to the bottom. On this axle 17 is 90 wound a flexible chute which is made of canvas or other suitable material and which 95 comprises a bottom portion 27 and side por- 100 tions 28, the latter being normally folded down on the bottom portion as shown in Fig. 5. In this condition the chute is rolled up on the axle 17. It is to be noted that the bottom of the chute is provided at in- 105 tervals along each edge with openings 29 which, when the chute is unrolled, engage the pins or projections 14 and thus prevent lateral sagging. The edges of the chute are reenforced as at 30, and these reenforced portions are engageable at the lower end of the device, by arms 31 operated by a shaft carrying an operating lever 32, the shaft being held in adjusted position by a pawl 33^a 110 engaging a shaft carried ratchet 33.

In using the device it is normally in the position shown in Fig. 1. In case of a fire any person within reach of the drop line 24 grasps the same and pulls upon it thereby 115 releasing the pawl 23 and permitting the axle 17 to roll down the rails 15 until it

reaches the bottom position whereupon the hooks 26 are engaged therewith. The upper end of the chute is permanently secured to the upper end of the run way at 27^a and thus it is stretched out on the angle irons 13. The side walls are then raised, and by engagement with the arms 31, are held in the raised position so that the chute assumes a trough shape. The occupants of the building may then pass out of the windows and slide down the chute to the bottom thereof. When the fire is out and the chute no longer in use, it may be folded up and re-rolled on the axle, this being accomplished by actuation of the winding drum 19 by a suitable crank.

It is obvious that the material of which the chute is made will be preferably of fire-proof nature, and to this end properly fire-proof canvas or any other desired material may be used.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is wished to include all such as properly come within the scope claimed.

Having thus described the invention, what is claimed as new, is:

1. In a fire escape, an inclined frame including upper and lower trackways, a roller rolling on said upper trackways, and a chute normally wound on said roller and having one end connected to the upper end of the lower trackway, said roller delivering the chute to the lower trackway during its downward movement along the upper trackway.

2. In a fire escape, an inclined frame including upper and lower trackways, a roller rolling on said upper trackways, a chute normally wound on said roller and having one end connected to the upper end of the lower trackway, said roller delivering the chute to the lower trackway during its downward movement along the upper trackway, and means to reroll the roller upwardly on the upper trackway.

3. In a fire escape, an inclined frame including upper and lower trackways, a roller rolling on said upper trackways, a chute normally wound on said roller and having one end connected to the upper end of the lower trackway, said roller delivering the chute to the lower trackway during its downward movement along the upper track-

way, means to reroll the roller upwardly on the upper trackway, and cooperating means on the lower trackway and chute to engage and hold the chute spread across the lower trackway upon unrolling thereof.

4. In a fire escape, an inclined frame including upper and lower trackways, a roller rolling on said upper trackway, and a chute normally wound on said roller and having one end connected to the upper end of the lower trackway, said roller delivering the chute to the lower trackway during its downward movement along the upper trackway, said chute consisting of a flexible bottom and flexible sides normally folded on said bottom.

5. In a fire escape, an inclined frame including upper and lower trackways, a roller rolling on said upper trackway, a chute normally wound on said roller and having one end connected to the upper end of the lower trackway, said roller delivering the chute to the lower trackway during its downward movement along the upper trackway, said chute consisting of a flexible bottom and flexible sides normally folded on said bottom, and means to reroll the roller upwardly on the upper trackway.

6. In a fire escape, an inclined frame including upper and lower trackways, a roller rolling on said upper trackway, a chute normally wound on said roller and having one end connected to the upper end of the lower trackway, said roller delivering the chute to the lower trackway during its downward movement along the upper trackway, said chute consisting of a flexible bottom and flexible sides normally folded on said bottom, means to reroll the roller upwardly on the upper trackway, and cooperating means on the lower trackway and chute to engage and hold the chute spread across the lower trackway upon unrolling thereof.

7. In a fire escape, an inclined frame including upper and lower trackways, a roller rolling on said upper trackway, a chute normally wound on said roller and having one end connected to the upper end of the lower trackway, said roller delivering the chute to the lower trackway during its downward movement along the upper trackway, means to reroll the roller upwardly on the upper trackway, comprising grooved pulleys on the ends of said roller, a winding drum at the upper end of said guide ways, and ropes wound on said drum and led around said pulleys back towards the drum and there secured.

In testimony whereof I affix my signature.
LEON M. LITTLE.
